KILN CAR DECK SUPPORT

Filed Jan. 7, 1927

UNITED STATES PATENT OFFICE.

CHARLES W. LASCHENSKI, OF TRENTON, NEW JERSEY, ASSIGNOR TO NEW CASTLE REFRactories COMPANY, OF NEW CASTLE, PENNSYLVANIA, A CORPORATION OF DELAWARE.

KILN-CAR-DECK SUPPORT.

Application filed January 7, 1927. Serial No. 159,655.

The general object of my present invention is to provide improved means for supporting the load-carrying super-structure of a kiln car such as is used in tunnel kilns and analogous industries. More specifically, the object of my invention is to provide an improved removable supporting element, or post, for supporting the upper deck or decks of a kiln car having two or more decks on which ware is carried through a tunnel kiln for appropriate heat treatment. My improved supporting post is made of fire clay or analogous material, and is characterized by its construction in separable parts so shaped that the effective length of the post may be varied by a simple adjustment of one of its parts relative to the other.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:—

Fig. 1 is an elevation partly in section showing my invention in use on a kiln car; Fig. 2 is an elevation of one form of post; Fig. 3 is an elevation partly in section of a modified form with the component parts separated; Figs. 4, 5, and 6 are views of other modified forms of cap pieces.

In the drawings is shown an open deck tunnel kiln car A, having the usual wheels and supporting base and carrying three decks A', A'', and A''', each consisting of a plurality of flat slabs of refractory material. The upper decks are supported by vertical post elements B and D of various forms and construction. Some of the supporting posts designated by the letter B may be of the usual hollow cast fire clay type, while others may be of the adjustable form which is the subject of the present invention.

In Figs. 1 and 2 of the drawings is shown

a simple form of adjustable post D consisting of a base or body portion and a top or cap portion E. The body portion of the post D is of cast or pressed fire clay or other suitable refractory material, and, as shown, is formed with an axial passage D' extending from its lower end upward for the greater part of the length of the post. At its upper end the part D is formed with an integral cylindrical tenon-like extension D² of reduced cross-section. The upper end surface of the annular portion of the base D surrounding the base of the projection D² is of screw or cam form being formed, as shown, to provide two similar inclined surface portions or sections D³ and D⁴, each extending half way around the tenon D². The top or cap section E of the post which may be made of the same material as the body portion of the post D, is formed with an axial passage or socket E' in its lower end in which the tenon portion D² of the body portion of the post D fits and is rotatably received. The lower end surface of the member E is screw or cam shaped, comprising sections E² and E³ shaped similarly to, and contacting with the surfaces D³ and D⁴.

The effective length of a post formed as described of a part D and a part E may be varied by rotating one part relative to another. In Fig. 1, the adjustable post beneath the upper deck A''' is shown in its contracted form in which it does not engage the deck A''' and, hence, may be readily removed and replaced preparatory to, and at the respective ware unloading and loading operations. The adjustable post D, shown as forming one of the supports for the car deck A'', has its cap portion E rotated relative to the body portion. To facilitate the relative rotation of the post sections to expand or increase the length of the post so that the latter will take its proper share of the weight of the platform A'', the two sections of the post are shown as formed with holes E⁴ and D⁵ in which bars or like implements may be inserted. The top and bottom section of each adjustable post may be positively secured in their adjusted position by wedging a piece of clay

F or other material in the recess formed between the end of the cam portions as shown in Fig. 1. Ordinarily, the use of such wedging material is unnecessary as the friction between the contacting surfaces is usually sufficient to prevent the parts slipping from their adjusted positions.

The form of post shown in Fig. 2 with its spherical top does not provide a large surface in contact with the slab or deck portion which it engages and supports. Various arrangements are shown in Figs. 3-6 by which the contact area is increased, and an even bearing surface provided when the slab is not exactly at right angles to the post. In these Figs. 3 to 6 posts are shown as provided at their upper ends each with a separate auxiliary cap piece or bearing member having spherical contact with an adjacent surface of the top section. In Fig. 3 the bearing member G is shown as having a flat top portion G' and a depending tenon G² received in a cylindrical socket E⁵ in the upper end of the cap section EA and of slightly larger diameter than the tenon G². The tenon G² is formed with a spherical bottom portion. With this arrangement the axis of the bearing part G may be slightly inclined to the axis of the post proper as required to engage the slab above without affecting the efficiency of the support.

In Fig. 4, the bearing member GA is provided with a convex bottom surface G³ resting in a concave surface of greater diameter formed in the top of the cap section EB of the post. In Fig. 5 the bearing member GB is provided with a concave recess G⁴ in its lower surface in which fits a convex projection on the upper end of the cap section EC. In Fig. 6 the bearing member GC is formed with a substantially spherical knob projection G⁵ engaging in a similarly shaped recess in the top section ED. On the top surface of each of the members GB and GC shown in Figs. 5 and 6 are provided slightly spaced projections G⁶ for engaging the slab which is supported by the member.

My improved posts with their self contained length adjusting provisions are simple and effective. They are appreciably easier to install and adjust than the non-adjustable posts heretofore employed which have been secured in place by separate wedge parts which are sometimes shaken out of place. In former designs separate wedges were used to raise the posts. These wedges had a tendency to slip out of position when suddenly jarred. In the present invention the wedge is incorporated in the post itself.

While in accordance with the provisions of the statutes, I have illustrated and described the best form of embodiment of my invention now known to me, it will be apparent to those skilled in the art that changes may be made in the form of the

apparatus disclosed without departing from the spirit of my invention as set forth in the appended claims and that in some cases certain features of my invention may be used to advantage without a corresponding use of other features.

Having now described my invention what I claim as new and desire to secure by Letters Patent is:-

1. A self contained adjustable deck supporting post for a kiln car formed of relatively axially movable refractory parts to vary the effective length of said supporting post.

2. A deck supporting element for kiln cars comprising a base portion and a cap portion of refractory material rotatably connected and adapted by their relative rotation to vary the effective length of said supporting element.

3. A deck supporting element for kiln cars comprising a base portion and a cap portion of refractory material rotatably connected and adapted by their relative rotation to vary the effective length of said supporting element, and means for holding said portions in the adjusted position.

4. A deck supporting element for kiln cars comprising a base section and a cap section of refractory material in rotatable engagement with one another and having contacting surfaces inclined to their axes of relative rotation whereby the height of said supporting element may be varied when the sections are relatively rotated.

5. A deck supporting element for kiln cars comprising a base member of refractory material having a tenon-like projection at its upper end, a cap member of refractory material having a socket in its lower end in which said projection is rotatably received, said members having cooperating inclined contact surfaces whereby the height of said supporting element may be varied by rotating said cap member relative to said base member.

6. A deck supporting element for kiln cars comprising a base member of refractory material having a tenon-like projection at its upper end, a cap member of refractory material having a socket in its lower end in which said projection is rotatably received, said members having cooperating inclined contact surfaces whereby the height of said supporting element may be varied by rotating said cap member relative to said base member, the contacting portions of said members being shaped to provide a recess in which clay may be inserted to lock the parts against rotation in the direction to shorten the length of the post.

7. An adjustable deck support for a kiln car superstructure comprising a base section member, a cap member rotatably connected to said base member, said members being

formed of refractory material, and having inclined contacting surfaces whereby the effective length of said support may be varied by the relative rotation of said members, and a deck engaging bearing block rotatably mounted on said cap member and adjustable thereon to accommodate surface

irregularities of the bearing block and deck portion engaged by the latter.

Signed at Trenton, in the county of Mercer, and State of New Jersey, this 3rd day of January, A. D. 1927.

CHARLES W. LASCHENSKI.
